US00D984994S

(12) **United States Design Patent** (10) **Patent No.:** **US D984,994 S**
He et al. (45) **Date of Patent:** **** May 2, 2023**

(54) **SMARTWATCH**

(71) Applicant: **SHENZHEN DO INTELLIGENT TECHNOLOGY CO., LTD.,**
Guangdong (CN)

(72) Inventors: **An He**, Shenzhen (CN); **Yuanyuan Chen**, Guangdong (CN)

(73) Assignee: **SHENZHEN DO INTELLIGENT TECHNOLOGY CO., LTD.,** Shenzhen (CN)

(**) Term: **15 Years**

(21) Appl. No.: **29/825,931**

(22) Filed: **Feb. 7, 2022**

(30) **Foreign Application Priority Data**

Nov. 29, 2021 (CN) 202130786004.8

(51) LOC (14) Cl. **14-02**

(52) U.S. Cl.

USPC **D14/341**; D24/167

(57) **CLAIM**

The ornamental design for a smartwatch, as shown and described.

DESCRIPTION

FIG. 1 is a front, right and top side perspective view of a smartwatch, showing our new design.

FIG. 2 is a rear, left and bottom side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines shown in the drawings represent portions of the smartwatch that form no part of the claimed design.

1 Claim, 8 Drawing Sheets
